UNITED STATES PATENT OFFICE

144,121

DESIGN FOR A CALENDAR

John Donald Maclean, Inverness, Scotland

Application May 5, 1945, Serial No. 119,416

Term of patent 14 years

(Cl. D74—5)

To all whom it may concern:

Be it known that I, John Donald Maclean, a subject of the King of Great Britain and Northern Ireland, residing at Inverness, Scotland, have invented a new, original, and ornamental Design for a Calendar, of which the following is a specification, reference being had to the accompanying drawings forming part thereof.

Figure 1 is a plan view of a calendar showing my new design, the back of same being plain.

Figure 2 is a plan view of the movable part of the calendar.

Fig. 3 is a side elevational view of the calendar as shown in Figure 1.

I claim:

The ornamental design for a calendar, as shown and described.

JOHN DONALD MACLEAN.
